UNITED STATES PATENT OFFICE.

CHARLES JOHN RICHARDSON, OF TEAM VALLEY PAPER MILLS, GATESHEAD-ON-TYNE, ENGLAND.

APPARATUS FOR THE MANUFACTURE OF PAPER.

SPECIFICATION forming part of Letters Patent No. 338,364, dated March 23, 1886.

Application filed January 12, 1886. Serial No. 188,345. (No model.)

To all whom it may concern:

Be it known that I, CHARLES JOHN RICHARDSON, a subject of the Queen of Great Britain, a resident of Team Valley Paper Mills, 5 Gateshead - on - Tyne, England, paper-manufacturer, have invented certain new and useful Improvements in Apparatus for the Manufacture of Paper, of which the following is a specification.

10 The object of the invention is to afford increased facility for effecting changes in the width of paper during manufacture without necessarily stopping the paper-making machine.

15 As paper-machines are now generally arranged the "deckle-frames" which regulate by their position the width of the paper, are pushed in or drawn out by hand when an alteration in the width of the paper is required, 20 and the "apron" or "lip" which is attached to them has also to be rolled up or spread out, as the case may be, by hand. This operation can only be carried out well when the paper-machine is at rest, thus involving loss 25 of time and material by a stoppage. The two deckle-frames can also only be dealt with one after the other unless a double staff of men be used.

According to my invention the deckle- 30 frames are made to move in or out simultaneously under the manipulation of a single man without any stoppage of the paper-making machine, while the action of the same mechanical means rolls up or spreads out the 35 apron in the required manner. The deckle-frames are carried by two parallel horizontal bars extending across the machine. These bars are geared together so that they can be turned simultaneously by one hand-wheel. 40 By means of right and left hand screw-threads upon them the deckle-frames are moved in and out when the bars are turned. The deckle-frames carry the wheels on which the deckle-straps run. They also carry horizontal rollers 45 on which the apron is wound as the deckle-frames approach, and from which it is unwound as they recede from each other. A cord and weight in connection with each roller keeps the apron always strained. The slices 50 also which regulate the flow of the pulp are connected with the deckle-frames and move

in and out with them, sliding the one on the other.

Figure 1 of the annexed drawings is a half-plan of the deckle-frames and other apparatus 55 concerned in the alteration of the width of the paper. Figs. 2 and 3 are sectional elevations of the same. The sections are taken on the lines A B and C D in Fig. 1, respectively.

a a are two round bars supported in bearings *b b* on the side frame, *c*, of the paper-machine. There are screws on the bars *a*, and the threads of these screws are right-hand on one side of the machine and left-hand on the other.

d is one of the deckle-frames. There is a similar frame on the other side of the machine.

e is a hand-wheel, by which the bars *a* can be simultaneously turned, the bars being geared together by means of chain-wheels and 70 an endless chain, *f*. Hence, when the hand-wheel is turned, the deckle-frames (with the parts which they carry) approach to or recede from each other. The plate *d'* forms a part of the deckle-frame, and it constitutes 75 one side of the trough *g*, from which the paper-pulp is delivered onto the traveling web of the machine.

H is the deckle-wheel. It is carried by an axis on the deckle-frame, and the endless 80 deckle-strap *K* runs around it. The width of the paper depends on the position of the deckle-straps, and is controlled by them in the usual way.

L is a roll, carried by brackets fixed to the 85 inner side of the plate *d'*. The ends of the apron *M* are fixed to the rolls *L* on either side of the machine. Each roll *L*, at one end, is provided with a small barrel, *N*, to which a cord, *O*, is attached. It is lapped around the 90 roll and at its farther end it carries a weight, *P*, tending to wind up the apron on the barrel and keep it tight, but, nevertheless, allowing the apron to unwind from the roll *L* when the deckle-plates are moved farther apart. 95 The slices *R R*, which control the flow of the pulp, are jointed together at the center, so as to admit of their sliding in and out, and they are self-supporting. Their ends are received into guide-grooves *Q* in the plates *d'*, in which 100 they are adjustable vertically by the thumb-screws *S*.

I claim—

1. The combination of the deckle-frames *d* and the screwed bars *a*, or equivalent parts, which move the two deckle-frames simultaneously in opposite directions.
2. The combination, with the apron *M*, of movable rollers *L*, and cords and weights *O* and *P*, or equivalent parts, which keep the apron strained between the rollers.
3. The combination, with the deckle-frames *d*, of the jointed slices *R R*.

4. The combination of the deckle-frames, the gear connecting the deckle-frames, the apron, and mechanism carried upon the deckle-frames which spreads and rolls up the apron, substantially as described.

CHARLES JOHN RICHARDSON.
